UNITED STATES PATENT OFFICE.

GUY H. MOYER AND ROBERT F. AUCKER, OF FREEBURG, PENNSYLVANIA.

FOLDING PIANO-SHIPPING CASE.

Application filed October 27, 1925. Serial No. 65,237.

This invention relates to improvements in knock-down or collapsible piano boxes which may be made of wood or metal and adapted to be used any number of times by 5 returning the box in its knock-down form for subsequent shipments of pianos.

The various features of the invention will be more fully described in connection with the accompanying drawings, in which:—

10 Figure 1 is a perspective view of a piano box showing the parts assembled when box is closed.

Figure 2 is a transverse section taken on line 2—2 of Fig. 1.

15 Figure 3 is a vertical sectional view of the back of the box.

Figure 4 is a perspective view of the piano box showing the front disengaged from the top and half of the ends disengaged for the 20 purpose of lowering the front preparatory to taking out or putting in a piano.

Figure 5 is a perspective view of the piano box when in a knock-down condition.

Referring now to the drawings, our improved piano box comprises a back portion 1 to which rectangular top and bottom sections 2 and 3 respectively, are hinged. The side edges of the back 1 are connected to sectional side pieces 4 and 4' by hinges 30 which are secured to the inner face of the back and side pieces.

The connected portions just described constitute the rear assembly of the piano box to which the front assembly, now to be described, is connected by detachable hinge portions as best shown in Fig. 4.

To the forward edges of the rear sectional side pieces 4 and 4' are connected, by detachable hinge sections 6 and 6', front sectional 40 side pieces 5 and 5', the connected side pieces being held against folding inwardly, when set up as shown in Figs. 1 and 2, by the angle irons 7 and 8 and 7' and 8', which are secured to the inner faces of the top and bottom respectively.

To the forward vertical edge of the side pieces 5 and 5' is hinged the lower front

section 10, and an upper front section 11 is hinged to the upper edge of the lower section. 50

By reference particularly to Figs. 1 and 4, it will be seen that the upper edge of the front section 11 and the lower edge of the front section 10 are connected with the forward edges of the top 2 and bottom 3, by 55 detachable hinge portions 12 and 13 respectively, which, in the set-up position, securely holds the front and rear assemblies together.

When it is desired to open the assembled box for the purpose of removing the enclosed piano, the pintles are removed from the detachable hinge portions 6 and 6' and 60 12, which will permit of the front assembly to be swung down on the hinge connections 13, as shown in Fig. 4. If desired the front 65 assembly can be entirely detached from the rear assembly by also removing the pintles from the detachable hinges 13 as shown in the knock-down position shown in Fig. 5.

After the piano has been removed from 70 the box, and it is desired to return the box for subsequent shipments, the front and rear assemblies may be folded separately and laid one upon the other, as shown in Fig. 5, or the pintles may be replaced in the hinge 75 portions 6 and 12, and with the pintles removed from the detachable hinge portions 12 and 13, the top 2 and bottom 3 may be folded back upon the outer surface of the back 1, as is also shown in Fig. 5. The angle irons 7 80 and 8 and 7' and 8' are thus removed from behind the foldable side sections 4 and 5 and 4' and 5', permitting these sections to be folded inwardly between the front sections 10 and 11 and the back 1, as will be 85 readily understood.

What we claim as new and desire to secure by Letters Patent, is:—

1. A foldable piano box comprising front and rear portions, said front portion comprising a front wall and side walls hingedly connected thereto, said rear portion comprising a rear wall having top, bottom and side walls hingedly connected thereto, and de- 90 95

tachable hinge sections connecting said front and rear portions.

2. In a piano shipping box the combination of a back, the top, base and sides having an edge of each hingedly secured thereto, a front detachably secured to the base and top by detachable hinge sections and having side

sections hingedly secured to the sides of said front, and detachable hinge sections connecting the side sections of said front and back, 10

In testimony whereof we affix our signatures.

GUY H. MOYER.
ROBERT F. AUCKER.
